UNITED STATES PATENT OFFICE

2,452,680

CURTAIN AND SHADE SUPPORT

Robert E. Ratcliffe, Dallas, Tex.

Application November 25, 1944, Serial No. 565,088

2 Claims. (Cl. 248—252)

1

This invention relates to a combined curtain and shade support and it is one object of this invention to provide a support consisting of a main bracket adapted to be mounted against a window casement or frame, and an auxiliary bracket carried by the main bracket and extending upwardly therefrom, said brackets being formed of plastic, metal, or other suitable material, by moulding, extruding, casting, or in any other suitable manner and of such formation that the auxiliary bracket may be very easily applied to or removed from the main bracket but firmly held when in place.

Another object of the invention is to so form the auxiliary bracket that it may hold a curtain pole of large diameter and also a flat curtain rod which is engaged in a seat formed at the upper end of an arm constituting the forward portion of the seat for receiving the large curtain pole.

Another object of the invention is to so form the seat for the flat curtain rod that when the rod is fitted within the seat it may be firmly held therein.

Another object of the invention is to so form the main bracket that Venetian blinds may be suspended between them.

Another object of the invention is to provide a main bracket so formed that its rear end portion may fit within the upper portion of a track for the lower sash and have associated with it a bracket for mounting a shade roller.

The invention is illustrated in the accompanying drawings, wherein;

Fig. 1 is a perspective view showing the improved curtain and shade support mounted upon a window frame.

Fig. 2 is a view showing the upper portion of the window frame in vertical section and the improved curtain and shade support in side elevation.

Fig. 3 is a view on the line 3—3 of Fig. 2.

Fig. 4 is a sectional view on the line 4—4 of Fig. 2.

Fig. 5 is a fragmentary sectional view on the line 5—5 of Fig. 3.

Fig. 6 is a perspective view of the auxiliary bracket.

Fig. 7 is a perspective view of the main bracket.

Fig. 8 is a perspective view showing the auxiliary bracket applied to the main bracket.

Fig. 9 is a perspective view of the auxiliary bracket with a flat curtain rod applied thereto.

Fig. 10 is a perspective view showing a portion of the auxiliary bracket with a flat curtain rod mounted in another position.

Fig. 11 is a perspective view of a bracket for carrying a shade roller.

This improved curtain and shade support is used for supporting shade rollers, Venetian

2

blinds, and various types of curtain poles and rods across the upper portion of a window frame F, the supports being mounted at opposite sides of the frame, as shown in Fig. 1. The supports are of duplicate construction and each includes a main bracket 1 and an auxiliary bracket 2 detachably applied to the main bracket, the main bracket also having associated with it a bracket 3 for carrying a shade roller. The brackets are preferably formed of plastic but it will be understood that metal or other materials found suitable may be used and that the brackets may be formed by moulding, extruding, casting, or in any other practical manner.

15 The main bracket has a shank 4 which has its rear portion bent laterally, as shown at 5, to provide an offset rear end 6 formed with openings 7 to receive securing screws 8 by means of which this attaching portion 6 is firmly secured in the track 9 for the inner sash of the window. An arm 10 projects transversely from the front end of the shank for extending across the adjacent side portion of the frame F. A tongue 11 is spaced forwardly from the arm 10 20 in substantially parallel relation thereto and, at its outer end, is connected with the arm by an end bar 12 carrying a boss 13 formed with a bore 14, through which the shank of a bracket for carrying overdraperies may be mounted. There has also been provided a web 15 extending between the arm and the tongue in spaced relation to the end member 12 and constituting a wall for a socket 16 to receive the lower end of the auxiliary bracket 2 and removably mount the auxiliary bracket in upright position over the outer end of the main bracket.

25 The auxiliary bracket 2 is also formed of plastic or other suitable material and has a shank 17, the lower end of which is formed with a U-shaped foot 18 of such dimensions that it fits snugly into the socket 16 of the companion main bracket. A tongue 19 extends from the free arm of the foot for resting upon the portion of the arm 10 which forms the rear arm of the socket 16 and opposite this tongue the shank carries a rib 20 for resting upon the front wall of the socket. The tongue and the rib will serve very effectively to limit downward movement of the foot 18 into the socket 16 and also to prevent the auxiliary bracket from tilting forwardly or rearwardly out of a perpendicular position. Since the material at the bottom of the foot is comparatively thick the foot will not be liable to be broken. At its upper end, the shank terminates in a forwardly curved bill 21 and in spaced relation to its upper end, the shank carries a forwardly extending upwardly curved arm 22 which cooperates with the upper portion of the shank to form a head having front and rear forks and adapted to receive a curtain pole 23 and remov-

ably support the pole across the window frame. The arm or front fork 22 terminates in fingers 24 terminating in rearwardly bent ends 25 for engaging across the pole 23, and through the bent ends of the fingers are formed openings 26 through which the shank of a hook 27 may be passed, as shown in Fig. 8, to engage the pole and assist in preventing accidental dislodgement of the pole. The hook 27 serves as a carrier for a ring 28 which serves as an anchor for a curtain and the hook will serve to prevent accidental dislodgement of a flat curtain rod 29 snapped into place between the fingers and supported across the window frame, as shown in Fig. 9. Instead of mounting the flat extensible curtain rod 29 between the fingers 24, it may be mounted under the fork 22 and rest upon a bill 30 where it will be gripped by the bill and the fork or arm and firmly held in place. Referring again to Fig. 8, it will be seen that the flat curtain rod 29 may be mounted between the tongues 11 of the two brackets with the tongues wedged into ends of the rods, as shown in Fig. 3, where the rod is indicated by dotted lines and the tapered tongue shown wedged into the rod.

The bracket 3 for mounting a shade roller is disposed in the upper portion of the track 9 for the inner or lower window sash and has a head or body 31 formed with transverse ribs 32 defining a seat 33 to receive the rear end portion 6 of the main bracket. Openings 34 are formed in the head 31 to register with the openings 7 and accommodate the screws 8 so that the screws serve to secure the bracket 3 as well as the main bracket. 1. A tongue 35 projects downwardly from the body portion of the bracket 3 and, at its lower end, carries a socket 36 formed with an opening 37 which may be circular, as shown in Fig. 11, to receive the pintle of a shade roller, or rectangular, in order to receive the key for the spring of the roller. In addition to serving as supports for window shades and curtain rods or poles, the brackets may also serve as means for mounting Venetian blinds, such use being illustrated in Fig. 8, where the head bar 38 of Vene-

tian blinds of conventional construction has been shown extending between the supports and provided at each end with a clip 39 for engaging the shank 4 of the adjacent auxiliary bracket.

5 Having thus described the invention, what is claimed is:

1. A support of the character described comprising a main bracket adapted to be secured to a window frame and provided with a socket open at upper and lower ends, and an auxiliary bracket 10 over the main bracket including a vertical shank having its lower end removably engaged in said socket, front and rear forks carried by said shank and curved towards each other for fitting about 15 the curtain pole, and one fork terminating in inner and outer fingers formed with openings for receiving a fastener to hold a curtain rod between the fingers and projecting from the inner finger to engage a curtain pole and hold the same 20 between the forks.
2. A support of the character described comprising a main bracket adapted to be secured to a window frame and provided with a socket open at upper and lower ends, and an auxiliary bracket 25 over the main bracket including a vertical shank having its lower end removably engaged in said socket, forks carried by said shank for receiving a curtain pole, said forks having upper portions curved toward each other, and a bill projecting 30 forwardly and upwardly from said shank under one fork and cooperating therewith for holding a curtain rod.
